United States Patent

Des. 235,645
Patented July 1, 1975

235,645

COMBINED COUNTER, SINK, STORAGE AND INDUCTION HEATING ELECTRIC COOKING RANGE UNIT

Philip H. Peters, Jr., Washington County, and John L. Matrone, Albany County, N.Y., assignors to Environment/One Corp., Schenectady, N.Y.

Original design application Sept. 23, 1971, Ser. No. 183,289. Divided and this application Nov. 12, 1973, Ser. No. 424,105

Term of patent 14 years

Int. Cl. D6—04; D7—02; D23—02
U.S. Cl. D23—50

FIG. 1

Des. 235,645

PAGE 2

FIG. 2

FIG. 3

FIG. 1 is a perspective view of the top, front and one end of a combined counter, sink, storage and induction heating electric cooking range unit showing our new design.

FIG. 2 is a top plan view thereof.

FIG. 3 is a front elevation thereof.

FIG. 4 is a rear elevation thereof.

FIG. 5 is an end elevation as seen from the left of FIG. 4.

FIG. 6 is an end elevation as seen from the right of FIG. 5.

This application is a division of our co-pending design application, Ser. No. 183,289, filed Sept. 23, 1971.

We claim:

The ornamental design for a combined counter, sink, storage and induction heating electric cooking range unit, as shown.
